HEADER BOARD STAKE

Charles B. Polhemus, San Jose, Calif.

Application July 27, 1931. Serial No. 553,274

1 Claim. (Cl. 25—118)

The present invention relates particularly to a stake for use in holding a header board in position during the construction of a concrete curb, sidewalk, or similar structure.

5 It is one object of the invention to provide a stake of the character indicated that may be used repeatedly without material deterioration.

It is another object of the invention to provide 10 a stake of the character indicated so shaped and formed as to be readily driven into the ground and yet be firmly imbedded in the ground and supported against accidental displacement in any direction.

It is also an object of the invention to provide 15 a stake of the character indicated that will be economical to manufacture, strong, rigid, durable, and highly efficient in its practical application.

In the drawing:

20 Figure 1 is a side elevation of a stake embodying my invention in position, parts broken away and partly in section.

Figure 2 is a section on line 2—2 of Figure 1.

25 Figure 3 is a section on line 3—3 of Figure 1. Figure 4 is a face elevation of the entering end of the stake.

In the form of the invention disclosed the stake comprises a bar of sheet metal of suitable dimensions having the following characteristics.

30 The center of the bar, throughout its entire length, is flat as shown at 1 and the two side portions are symmetrically formed into concavo-convex portions as shown at 2—2. Through the center of the flat portion 1, and near the head of the bar, are formed holes as 3—3 through which nails as 4—4 may be driven into a header board 5. The entering end of the bar is formed into a blunt point 6 by cutting away angular portions on both sides thereof through the portions 2—2 as shown at 7. The convexity of the side portions 2—2 is increased at points adjacent the

base of the angular edges 7—7 as shown at 8—8 thereby causing the edges 9—9 to make a sharp twist at this point as shown at 10—10.

In applying the stake it is driven into the ground the desired distance with the concave 60 sides of portions 2—2 facing the board, and is nailed to the board with the flat portion 1 against the same.

A bar formed in this manner may be readily 65 removed from the board when the concrete is set and used again. It will not bend when being driven into the ground. A comparatively small area contacts the board, consequently it is easily mounted solidly thereon. Its cross-sectional conformation positively insures its entering the 70 ground in the direction selected, and effectually prevents lateral movement.

The bulging shoulders at 8—8 may not always be provided, but I have found that they counteract the tendency of the angular edges 7—7 to 75 force the entering end of the bar inwardly with respect to the desired position of the board 5, the inner sides of the shoulders as 11—11 bearing against the soil and holding the bar to its true position.

It is to be understood, of course, that while I have herein shown and described but one specific embodiment of the invention, changes in form, construction and method of application 85 may be made within the scope of the appended claim.

I claim:

A header board stake comprising a sheet metal bar having a cross-sectional configuration presenting a flat base portion and symmetrically formed concavo-convex side portions, the entering end of the stake having the said side portions bevelled and having bulbous portions formed at the base of the bevelled portions. 90
